UNITED STATES PATENT OFFICE.

DONALD M. McLEAN, OF BOSTON, MASSACHUSETTS.

CENTERBOARD.

No. 834,840.

Specification of Letters Patent.

Patented Oct. 30, 1906.

Application filed November 3, 1905. Serial No. 285,742.

To all whom it may concern:

Be it known that I, DONALD M. McLEAN, of Boston, in the county of Suffolk and State of Massachusetts, have invented certain new and useful Improvements in Centerboards, of which the following is a specification.

This invention has for its object to provide an improved centerboard for vessels, adapted to be raised and lowered by a flexible controller, such as a rope or chain, without liability of displacement of the controller from its proper position relatively to the centerboard, and therefore without liability of the fouling of the controller between the sides of the centerboard and the sides of the trunk or casing in which it moves.

The invention also has for its object to provide improved means for securing the centerboard in various positions.

The invention consists in the improvements which I will now proceed to describe and claim.

Of the accompanying drawings, forming a part of this specification, Figure 1 represents a side elevation of a centerboard trunk or casing, showing in dotted lines a centerboard embodying my invention. Fig. 2 represents a longitudinal section of the casing, showing the centerboard partially in section and partly in elevation, the centerboard being raised. Fig. 3 represents a view similar to Fig. 2, showing the centerboard lowered. Fig. 4 represents a view similar to Fig. 2, showing a different form and arrangement of the controller. Fig. 5 represents a section on line 5 5 of Fig. 4. Fig. 6 represents a side elevation of a portion of the centerboard-trunk, showing the securing device illustrated in section in Fig. 5. Fig. 7 represents a section on line 7 7 of Fig. 6. Fig. 8 represents a view similar to Fig. 6, showing a different form of centerboard-securing means. Fig. 9 represents a section on line 9 9 of Fig. 8. Fig. 10 represents an end view of the removable set-screw handle shown in Fig. 9. Fig. 11 represents a sectional view of a modification.

The same reference characters indicate the same parts in all the figures.

In the drawings, *a* represents a trunk or casing adapted to receive a centerboard *b*, the said trunk being suitably built into the hull of the vessel and open at its lower edge through the keel *c* of the vessel. The centerboard *b* is pivoted at *d* to the trunk, the pivot being located in close proximity to the keel and to the lower edge of the centerboard

when the latter is in its raised position. The pivot is also located considerably nearer the front end of the centerboard than the rear end to permit a considerable projection of the centerboard below the keel, as shown in Fig. 3, in which *b'* represents the forward edge of the centerboard. The back edge of the centerboard is provided with a slot or channel *b*², adapted to receive a flexible controller, whereby the centerboard is raised and lowered.

The controller may be a sprocket-chain *e*, as shown in Figs. 1, 2, and 3, or it may be a rope *e'*, as shown in Figs. 4 and 5, or the controller may be of any other suitable construction. One end of the controller is affixed to the centerboard at *b*³, the point of connection between the controller and the centerboard being at one end of the bottom of the slot *b*². Means are provided for guiding the controller in the plane of the slot *b*². Said means may be a guiding-orifice *f*, formed in the top of the trunk *a* above the rear portion of the centerboard or a guiding-orifice *f'*, formed in the forward end of the trunk, or a pulley *f*², journaled in the forward portion of the trunk and located between the centerboard, and an orifice *f*³ in the top of the trunk. In either case the guiding device is arranged to keep the controller in line with the slot. The slot is of sufficient depth to enable its sides to act as guards, preventing the controller from slipping sidewise from the centerboard and becoming fouled between the centerboard and either side of the trunk.

The bottom of the slot or channel is curved in the direction of the length of the centerboard, so that when said centerboard is lowered the flexible operating device or controller lies along said curved bottom and by said curvature is kept snugly against the bottom of the slot, so that there is little or no liability of seaweed or other material lodging against the flexible device and the bottom of the slot. This curvature insures the flexible controlling device resting in contact with the bottom of the well throughout the entire length of that portion which is below the surface of the water.

Owing to the fact that the bottom of the slot or channel *b*² is curved, as described, the rope or chain will closely fit the said bottom along practically the entire length thereof that is below the water-line, whether the centerboard is partially or fully lowered. This construction is particularly useful for the

purpose described when the said slot or channel is formed in the upper edge of the centerboard instead of in its rear edge, and the centerboard is mounted, as shown, to swing approximately ninety degrees. This is because in spite of the considerable range of movement there is no space between the rope or chain and the bottom of the channel at any point below the water-line into which seaweed could float and lodge, and said curve prevents any slack occurring in the rope or chain, due to drag by the water through which the vessel is sailing.

The centerboard is preferably so formed that when raised its forward edge b' will be elevated above the bottom of the keel, so that the centerboard will be protected by the keel in case the latter runs upon a rock or other obstruction. The forward edge of the centerboard is preferably recessed at b^5 to permit the solid portion of the keel to extend back nearly to the pivot d , thus reducing to the minimum the length of the opening through the keel for the accommodation of the centerboard and correspondingly increasing the strength of the hull at this point.

When the controller is a sprocket-chain e , the bottom of the slot b^2 is provided with sprocket-teeth e'' , adapted to engage the links of said chain, so that when the centerboard is lowered it is engaged with a large number of links, as shown in Fig. 3, the strain exerted on the securing pin or device b^8 being thus relieved and distributed along the links and teeth. The links may be numbered to indicate the depth to which the centerboard projects.

To enable the centerboard to be secured at various positions, I provide the trunk a with means for engaging the centerboard. In Figs. 5, 6, and 7 I show the securing means as a set-screw i engaging a threaded bushing j , affixed to one side of the trunk, the set-screw extending through one side of the trunk and bearing against a segmental metallic wear-plate k , affixed to the centerboard, said wear-plate being concentric with the pivot d .

In Figs. 8 and 9 I show a set-screw i' provided with a socket i^2 , adapted to engage a removable wrench or handle i^3 , the socketed set-screw being engaged with a bushing j' , affixed to the trunk a . The last-described construction enables the outer end of the set-screw to be substantially flush with the outer surface of the trunk when the handle i^3 is removed.

In Fig. 11 I show a pin m adapted to be inserted removably in orifices formed for its re-

ception in both sides of the trunk a and in either of a series of orifices n , formed in the centerboard, the said orifices n being arranged in segmental series.

I claim—

1. A centerboard mounted to swing approximately ninety degrees and having a slot or channel in its upper edge for the reception of a flexible operating device or controller, the bottom of said slot or channel being curved in the direction of the length of the centerboard to cause the said controller to be held in contact with the bottom of the channel at and below the water-line.

2. A centerboard mounted to swing approximately ninety degrees and having a curved slot or channel in its upper edge, combined with a trunk or casing to which the centerboard is pivoted, and a flexible controller secured to the centerboard between the sides of the slot, the said trunk and centerboard having means for guiding the controller.

3. A centerboard provided with a controller-receiving slot or channel, having sprocket-teeth at its bottom, combined with a sprocket-chain secured between the walls of the slot, and adapted to engage the teeth.

4. The combination of a trunk or casing, a centerboard pivoted thereto, and means supported by the trunk at a distance from the pivot for securing the centerboard to the trunk in various positions to prevent the centerboard from swinging in either direction.

5. The combination of a trunk or casing, a centerboard pivoted thereto, and a securing device supported by the trunk at a distance from the pivot and adapted to engage the centerboard to hold the latter in various positions and to prevent the centerboard from swinging in either direction.

6. The combination of a trunk or casing, a centerboard pivoted thereto, and provided with a segmental wear-plate concentric with the center of oscillation, and a set-screw engaged with the trunk and adapted to abut against said wear-plate.

7. A centerboard trunk or casing having an internally-threaded bushing, and a socketed set-screw engaged with said bushing and provided with a detachable handle, said set-screw being adapted to abut against a centerboard in the trunk or casing.

In testimony whereof I have affixed my signature in presence of two witnesses.

DONALD M. MCLEAN.
